US0D1074597S

(12) **United States Design Patent** (10) **Patent No.:** **US D1,074,597 S**
(45) **Date of Patent:** **** May 13, 2025**

(54) **CAPACITOR HOLDER**

(71) Applicant: **1NV3NT, LLC**, Hollywood, FL (US)

(72) Inventors: **Christopher McConnell**, Hollywood, FL (US); **Bryce Laufenberg**, Cooper City, FL (US)

(73) Assignee: **1NV3NT, LLC**, Hollywood, FL (US)

(**) Term: **15 Years**

(21) Appl. No.: **29/971,268**

(22) Filed: **Nov. 1, 2024**

(51) **LOC (15) Cl.** **13-02**

(52) **U.S. Cl.**

USPC **D13/118**

(58) **Field of Classification Search**

USPC D13/125, 184, 110, 117, 118, 123, 129

CPC H01G 2/02

See application file for complete search history.

(57) **CLAIM**

The ornamental design for a capacitor holder as shown and described.

DESCRIPTION

FIG. 1 is a top perspective view of the capacitor holder; FIG. 2 is a bottom perspective view of the capacitor holder shown in FIG. 1;

FIG. 3 is a right-side elevational view thereof, and a left-side elevational view is not shown because it is a mirror image of the right-side elevational view;

FIG. 4 is a front elevational view thereof;

FIG. 5 is a rear elevational view thereof;

(Continued)

FIG. 6 is a bottom plan view thereof; and,
FIG. 7 is a top plan view thereof.

The ornamental design which is claimed is shown in solid
lines in the drawings.

1 Claim, 6 Drawing Sheets

FIG. 1

FIG. 2

FIG. 3

FIG. 4

FIG. 5

FIG. 6

FIG. 7
